SPARK DISCHARGE CONTROL MEANS
Harold C. Early, Ann Arbor, Mich., assignor to Meredith
Publishing Company, a corporation of Iowa
Filed Mar. 6, 1961, Ser. No. 93,739
12 Claims. (Cl. 315—277)

This application relates generally to electrical control circuits for controlling the discharge of an electric spark and more particularly to new and improved spark discharge control circuits having use with multiple spark electrodes adapted for simultaneous energization in parallel discharge channels.

It is known in the prior art, as shown and described in Early et al. Patent No. 2,737,882, to print or perforate a rapidly moving web or tape utilizing the energy generated from the discharge of an electric spark. In high speed punching or printing apparatus, for example, a tape is fed between a pair of opposed, closely spaced surfaces which confine a space therebetween. One surface constitutes a die and the other constitutes an anvil to confine the gases between the tape and surface of the anvil. In the devices utilized in the past, a pair of electrodes projected into the confined space from the anvil side of the device. When a high voltage electrical spark is discharged across such electrodes, air or other gas which may be confined between the tape and the anvil is instantaneously heated and expanded. The force produced by the rapid expansion of the gas against the tape causes it to be embossed or perforated in a desired manner.

It has been found that a single spark channel is limited in width and may develop a localized pressure against the surface of the tape. In addition, punching some holes, such as a quarter inch diameter hole, requires such high current sparks that very rapid die chipping and electrode wear may result. Therefore, in certain instances, it is desirable to utilize two or more pairs of spark electrodes adapted to be simultaneously energized in parallel discharge channels to produce a more uniform pressure over a much larger area. The use of multiple spark electrodes gives rise to certain control circuit problems, and applicant has found it necessary to invent a new and highly useful electrical control circuit for controlling the arc discharge in multiple pair spark electrodes.

Accordingly, it is an object of this invention to provide new and improved electrical control circuitry for controlling the electric spark discharge of multiple pair spark electrodes adapted for simultaneous energization in parallel discharge channels.

More particularly, it is an object of this invention to provide such electrical control circuitry for multiple pair spark electrodes which utilizes balancing reactors to equalize the current in the parallel discharge paths.

The above and other objects are realized in accordance with the features of one illustrative embodiment of the invention wherein the electrical control circuit for the multiple pair electrodes comprises plural balancing reactors to equalize the current in the parallel discharge path. For example, in the case of a spark discharge circuit utilizing two electrode pairs, two balancing reactors are arranged such that one electrode of each pair is connected to the opposite terminals of one balancing reactor and the remaining electrode of each pair is connected to the opposite terminals of a second balancing reactor. Each balancing reactor is provided with a center tap, with the center tap of one balancing reactor being connected to ground and with the center tap of the other balancing reactor being connected through a switch to a source of potential such as the charged capacitor which, in turn, is returned to ground.

Advantageously, each balancing reactor is wound on a

2

pulse transformer core of highly laminated steel. The physical arrangement of the two windings on each core is designed to provide a maximum coefficient of coupling and a minimum leakage reactance between the winding on one side of the center tap and the winding on the other side of the center tap. When a spark is initiated by closing the switch, spark channels begin to form at the gaps between the electrode pairs. If the discharge currents are exactly equal, then the balancing reactor has essentially no effect on the circuit because the magnetizing force due to the current in one-half of the winding is cancelled by the current in the opposite half of the winding. However, if one spark channel starts to take more than one-half of the current, then the coupling between the windings causes the voltage across the other channel to increase and restore the equality of the two currents. As explained in greater detail hereinbelow, this principle may successfully be utilized in two or three or four pair electrode arrangements, or if desired, in any greater number of electrode pair arrangements which embody the present invention.

Thus, it is another object of this invention to provide a new and improved balanced reactor control circuit for controlling the spark discharge of a plurality of pairs of spark electrodes.

It is a further object of this invention to provide such an improved balanced reactor control circuit for plural pair spark electrodes which finds particular use in high speed spark discharge web punching or printing apparatus.

It is a still further object of this invention to provide a balanced reactor arc discharge control circuit, as above, which is characterized by its efficiency, its reliability, and its relative economy of construction and operation.

The novel features which are characteristic of the invention are set forth with particularity in the appended claims. The invention itself, however, both as to its organization and method of operation, together with further objects and advantages thereof, will best be understood by reference to the following description taken in conjunction with the accompanying drawings in which:

FIGURE 1 is a sectional view of one illustrative embodiment of the web punching apparatus capable of utilizing the plural spark discharge control circuit of the present invention;

FIGURE 2 is a view taken substantially as shown along line 2—2 of FIGURE 1 particularly illustrating the plural spark discharge electrode pairs utilized in the apparatus of FIGURE 1;

FIGURE 2a is an enlarged view of the multiple electrode pair and anvil assembly illustrating the spark discharge paths;

FIGURE 3 is a schematic diagram of an electrical control circuit for a two electrode pair spark discharge arrangement embodying the present invention;

FIGURE 4 illustrates the construction of a balancing reactor suitable for use with the control circuit of FIGURE 3;

FIGURE 5 is an electrical schematic diagram of a three spark electrode pair arrangement embodying the present invention;

FIGURE 6 illustrates the construction of a balancing reactor suitable for use with the control circuit of FIGURE 5;

FIGURE 7 is a simplified electrical schematic diagram of a control circuit for four spark electrode pairs embodying the present invention; and

FIGURE 8 is a simplified electrical schematic diagram of an alternative control circuit for four spark electrode pairs embodying the present invention.

Referring now to the drawing, and more particularly to FIGURES 1 and 2 thereof, there is shown one illustra-

tive web punching or printing apparatus adapted to be used with the multiple pair spark discharge control circuit of the present invention. As there shown, the apparatus comprises a vertical mounting plate 10, made from aluminum or other rigid material, which serves as a support and guide for the moving web W. Those skilled in the art will appreciate that the web W may be paper, coated fabric, a plastic sheet or other material which is to be perforated by the apparatus.

Suitable means (not shown) is provided for moving the web W upwardly across the face of plate 10 opposite the die assembly, which is indicated generally by the numeral 12. Such means may comprise part of another apparatus on which the web is being processed, e.g., a rotary printing press.

The anvil assembly is mounted on the other side of the plate 10 and is designated generally by the numeral 14. Advantageously, the anvil may comprise a knurled cylindrical disc 16 adapted to be driven by the rotatable shaft 18, such that an end face of the knurled anvil disc 16 is positioned adjacent the web W through an opening 20 in the mounting plate 10. The plural pair electrode assembly comprising the electrode pairs 24, 26, and 28 is mounted on the insulator blocks 22 and 30 by any suitable means, so as to be positioned in the opening 20 between the web W and the knurled anvil disc 16 in contact with the latter. Advantageously, the insulator blocks 22 and 30 are urged against the knurled anvil disc 16 by the biased pivoted arm weights 32 and 34.

The die 36 is mounted adjacent the web W opposite the electrode and anvil assembly, and the die 36 is provided with a suitable opening 38 in the face thereof to impart an embossment or perforation in the web W upon energization of the spark electrode pairs. The face of the anvil 16 adjacent the web W serves to confine gases between the web and the anvil for imparting such embossments or perforations in the web. The paths of the spark discharge at the knurled anvil surface is illustrated in FIGURE 2a by the heavy black lines.

Advantageously, the anvil 16 may be formed of any suitable non-inflammable dielectric resinous organic material since such material evaporates under the heat of the arc to provide additional quantities of gas. However, other materials, such as ceramic, also are satisfactory for this purpose. Obviously, the thickness of the web disc may be varied in accordance with the particular use to which the apparatus is put, and this thickness is not critical as long as the contact face of the anvil at least partially confines gas adjacent the web W.

Since it is essential that members in contact with the electrode assembly be completely insulated from the rest of the apparatus, an insert 40, made from Bakelite, or other dielectric material, is provided for the plate 10.

The die 36 mounted adjacent web W opposite the face of anvil 16 may be made of any suitable heat resistant dielectric material. The die 36 has an aperture 38 extending therethrough which determines the size of the opening punched through the web W. Manifestly, the opening 38 in a die 36 may be formed of any suitable size depending upon the size of the desired embossment or perforation in the web W, the function of the opening 38 being to impart physical indicia in the web W as the web is forced against it in response to the discharge of the spark electrodes.

As shown in the illustrative embodiment of FIGURE 1, the die 36 may be supported within a die holder 42 in the form of a ring mounted within a support ring 44 which, in turn, is secured to the yoke 46 by means of the pivot pins 48. Advantageously, the die holder 42 is made from a suitable dielectric material, as is the support ring 44. Yoke 42 is formed with an opening 50 extending therethrough, concentric with the die opening 38. This opening 50, in turn, communicates with a tube 52 connected to a source of vacuum. The vacuum connection not only serves to carry away those portions

of the web which may be punched out during perforating operation, but, in addition, it causes the web W to run in contact with the surface of the die. Those skilled in the art will appreciate that the exemplary apparatus described with respect to FIGURES 1 and 2 is merely illustrative of one of the uses of the present invention, and that the invention is not limited to such apparatus, but may be used with equally advantageous results in other types of spark discharge devices.

Reference now is made to FIGURES 3 and 4 of the drawing wherein one spark discharge control circuit embodying the present invention is shown as adapted to control the discharge of spark electrode member comprising two pairs of parallel aligned discharge electrodes.

15 The first pair of spark electrodes comprises electrodes 54 and 56, which are positioned adjacent the anvil 16 so as to define a spark gap A therebetween. The second pair of spark electrodes comprises electrodes 58 and 60 positioned adjacent the anvil 16 so as to define a spark gap B therebetween, which spark gap is parallel to the spark gap defined by electrodes 54 and 56.

As stated heretofore, the use of multiple electrode pairs for the parallel spark channels requires the use of balancing reactors to equalize the currents in the parallel paths. In accordance with the present invention, the electrodes 54 and 58 are connected to the end terminals of a balancing reactor 62, while the electrodes 56 and 60 are connected to the end terminals of a balancing reactor 64. Specifically, the spark electrode 54 is connected to the terminal 66 of balancing reactor 62 and the spark electrode 58 of the other parallel pair is connected to the end terminal 68 of balancing reactor 62. A center tap connection 70 on balancing reactor 62 is connected by the line 72 to a contact 74 of a power switch 76, the armature 78 of which is connected to a source of potential 80. In addition, the switch armature 78 is connected to a capacitor 82, which, in turn, is connected to ground. The spark electrode 56 is connected to the end terminal 84 of balancing reactor 64, while the spark electrode 60 is connected to end terminal 86 of balancing reactor 64. The center tap 88 on the balancing reactor 64 is connected to ground to complete the spark energization circuit.

The physical construction for one illustrative embodiment of balancing reactor which advantageously may be used with the invention is shown in FIGURE 4 of the drawing. In this embodiment, the balancing reactor 62 comprises a pair of oppositely wound windings on a pulse transformer core 90, which preferably is formed of finely laminated steel. As shown, the core 90 may be C-shaped with an air gap 92 between the closely spaced ends of the core. This air gap serves to reduce the remanence induction of the core so as to minimize the probability of repeating the single channel spark. The physical arrangement of the two windings on the core 90 advantageously provides maximum co-efficient of coupling and minimum leakage reactance between the winding on one side of the center tap 70 and the winding on the other side of the center tap 70.

It now will be understood by those skilled in the art that in the operation of the invention, the spark is initiated by closing contacts 74 and 78 of switch 76 to provide a voltage across the spark electrodes. At this time, parallel spark channels start to form at the spark gaps A and B between the parallel pairs of spark electrodes. If the spark discharge currents are exactly equal, the balancing reactors have essentially no effect on the discharge circuit because the magnetizing force due to the current flow in one-half winding in each balancing reactor is cancelled by the current flow in the opposite half winding of the balancing reactor. However, in accordance with the invention, should one spark channel start to make more than half of the current, the coupling between the windings on the balancing reactor causes the voltage across the other channel to increase and thereby restore the equality of the two currents. In this manner, the spark discharge

currents in the parallel paths are kept equal in an automatic and self-adjusting fashion to insure the stability and efficiency of the desired operation.

A spark discharge control circuit for a three-parallel channel spark discharge arrangement embodying the invention is illustratively shown in FIGURES 5 and 6 of the drawing. Thus, the spark electrodes 94 and 96 adjacent the anvil 16 define a spark gap therebetween to form one spark discharge channel, the spark electrodes 98 and 100 adjacent anvil 16 define a spark gap therebetween to form a second spark discharge channel, and the spark electrodes 102 and 104 adjacent anvil 16 define a spark gap therebetween to form the third spark discharge channel.

A first balancing reactor 104 is connected to the spark electrodes 94 and 102, with electrode 94 being connected to end terminal 108 of reactor 104 and spark electrode 102 being connected to end terminal 112 of reactor 104. The center tap terminal 110 of balancing reactor 104 is connected through a second balancing reactor 106 to the spark electrode 98.

Thus, the center tap 110 of reactor 104 is connected to terminal 114 of reactor 106 and terminal 118 of reactor 106 is connected to spark electrode 98. In a similar fashion, the spark electrodes 96 and 104 are connected to the reactor 122, with spark electrode 96 being connected to end terminal 126 of reactor 122 and with spark electrode 104 being connected to end terminal 130 of reactor 122. The center tap terminal 128 of balancing reactor 122 is connected to end terminal 132 of a fourth balancing reactor 124, with end terminal 134 of reactor 124 being connected to the spark electrode 100.

It will be noted with respect to the embodiment of the invention shown in FIGURE 5, that the reactor 106 is provided with an intermediate tap terminal 116 connected to reactor 106 at a point such that approximately one-third of the winding lies between terminals 114 and 116, and approximately two-thirds of the winding lies between terminals 116 and 118.

The intermediate tap terminal 116 is connected to a suitable source of potential 129 through the switch and capacitor arrangement shown with respect to FIGURE 3 of the drawing. Similarly, the intermediate tap terminal 136 of reactor 124 is connected such that one-third of the reactor winding lies between terminal 134 and 136, and approximately two-thirds of the reactor winding lies between terminal 136 and 132. The intermediate tap terminal 136 is connected to ground to complete the discharge control circuit.

As explained hereinbelow, approximately two-thirds of the reactor current flows between the intermediate tap terminal 116 and the end terminal 114 of reactor 106, and approximately two-thirds of the reactor current flows between the intermediate tap terminal 136 and end terminal 134 of reactor 124. In the physical construction of a reactor 106, it has been found advantageous to utilize a three-layer winding as shown in FIGURE 6 of the drawing. The innermost layer 144 and the outermost layer 142 are wound on the core 138 in one direction and are connected in parallel. These two windings constitute the leg of the reactor between the terminals 116 and 118. The middle layer 140 constitutes the leg of the reactor between terminals 114 and 116 and advantageously, this layer is wound in a direction opposite to that of the other two layers. In order to optimize the coupling, the middle layer 140 advantageously is wound from a double width conductor so that even though only one-half the number of turns is present, the physical length of the winding is the same as the inner and outer layers. This also serves to minimize the uncoupled leakage flux.

In the operation of the circuit shown in FIGURE 5 of the drawing, current I_0 entering reactor 106 at the intermediate terminal 116 divides to flow in both the left and right windings. As stated above, the winding between terminals 116 and 118 is provided with twice as

many turns as the winding between terminals 114 and 116. Hence, when the former winding carries half the current that is carried by the latter winding, the net magnetization of the core of reactor 106 is zero, and the reactive drop of the current pulse in the winding also is zero. The current thus divides so that one-third of the I_0 current goes to the electrode 98, and two-thirds of the I_0 current goes to the center tap 110 of reactor 104. Reactor 104 divides this current equally so that one-third 10 of the I_0 current goes to electrode 94 and the remaining one-third of the I_0 current goes to the electrode 102.

A similar arrangement of balancing reactors 122 and 124 is used with electrodes 96, 100 and 104 to insure that equal current will flow across the spark gap between the spark electrodes. In this manner, the spark discharge current is maintained equalized in an automatic and self-correcting fashion in the event the voltage across one pair of electrodes should tend to increase or decrease with respect to the voltage across the remaining spark electrode pairs.

FIGURES 7 and 8 of the drawing illustrate spark discharge control circuits embodying the invention suitable for use with four parallel spark channels. In the illustrative embodiment of FIGURE 7, the control circuit 15 comprises six balancing reactors connected such that the current flow in the discharge channels will be equalized to insure efficient and reliable operation.

Thus, as shown in FIGURE 7, the four parallel spark discharge channels include the electrode pairs 150 and 152, 154 and 156, 158 and 160, and 162 and 164. Electrodes 150 and 162 are connected to the opposite end terminals 166 and 168 of a balancing reactor 176. Electrodes 154 and 158 are connected to the opposite end terminals 172 and 174 of a balancing reactor 176. A center tap terminal 178 on reactor 176 is connected to a center tap terminal 180 on reactor 176 by means of a further balancing reactor 182. The center tap terminal 184 on reactor 182 is connected to a suitable source of voltage through suitable switch and capacitive circuitry as above described.

In a similar manner, electrodes 152 and 164 are connected to the opposite end terminals 186 and 188 of a balancing reactor 190. Electrodes 156 and 160 are connected to the opposite end terminals 192 and 194 of a balancing reactor 204. The center tap terminal 196 of reactor 204 is connected to the center tap terminal 198 of reactor 190 through the windings of the balancing reactor 200. The center tap terminal 202 of reactor 200 is connected to ground to complete the spark discharge control circuit.

Those skilled in the art will appreciate that the spark discharge control circuit shown in FIGURE 7 serves to insure equal current flow in each of the four parallel spark discharge channels. It further will be appreciated that the current flow in the balancing reactors will be divided equally to maintain the desired balanced condition.

An alternative embodiment of spark discharge control circuit for a four discharge channel arrangement is shown in FIGURE 8 of the drawing. The spark electrode pairs 60 comprise electrodes 208 and 210, 212 and 214, 216 and 218, and 220 and 222. As explained heretofore, each of the spark electrode pairs define an air gap or spark channel therebetween, said spark channels being aligned in parallel with each other adjacent the anvil (not shown.)

Spark electrodes 208 and 212 are connected to the opposite end terminals 226 and 228 of balancing reactor 224. Spark electrodes 216 and 220 are connected to the opposite end terminals 234 and 236 of balancing reactor 232. The center tap terminal 230 of reactor 224 is connected to the end terminal 242 of balancing reactor 240, while the center tap terminal 238 of reactor 232 is connected to the end terminal 246 of reactor 240. The center tap terminal 244 of reactor 240 is connected to a 70 source of potential at the terminal 248, which in turn is

connected to the appropriate switch and capacitance means of the type described hereinabove.

In a symmetrical fashion, spark electrodes 210 and 214 are connected to the opposite end terminals 252 and 254 of balancing reactor 250. Spark electrodes 218 and 222 are connected to the opposite end terminals 260 and 262 of balancing reactor 258. The center tap terminal 256 of reactor 250 is connected to the end terminal 268 of reactor 266 while the center tap terminal 264 of reactor 258 is connected to the end terminal 270 of reactor 266. The center tap terminal 272 of balancing reactor 266 is returned at the terminal 274 to the potential source to complete the spark discharge control circuit.

Those skilled in the art will appreciate the operation of the circuit shown in FIGURE 8 of the drawing. Due to the symmetrical arrangement of the various balancing reactors forming the circuit, the circuit serves to balance out any inequality in current flow across the parallel discharge channels. Thus, should the voltage at the discharge channel tend to rise, the balancing reactors effect an opposite condition to reassert equality of the voltages at the various discharge channels. In this manner, all of the multiple spark electrodes discharge channels may be simultaneously energized and still maintain equalized currents in the parallel discharge paths.

While the various balancing reactors shown in the drawing and described hereinabove may take any suitable form, in practice it has been found advantageous to utilize balancing reactors having the following characteristics. It is highly desirable that the co-efficient of coupling between the winding on one-half of the reactor and the winding on the other half of the reactor be as high as possible. In other words, magnetic flux which links one-half of the winding should, as far as possible, link the other half of the winding. Any flux which links part of the turns but does not link all of the turns of both windings is designated as leakage flux since it is not cancelled out by the opposite magnetomotive forces.

It also is important that the inductance of the winding as measured across the reactor be as high as possible in order to maximize the transformer action between the two halves of the reactor winding. It further has been found in the practice of the invention that the steel core of the reactor advantageously should be of thin laminations, such as one mil, to permit flux penetration into the steel at frequencies of many megacycles, since the frequency components involved in the operation of the reactor are very high, and substantial changes in currents occur in time intervals of a few thousandths of a microsecond. Ferrite cores have been used for this purpose, but they are less desirable than finely laminated steel cores because the ferrite materials saturate at a lower flux density and have lower permeability.

In one practical embodiment of the invention, which has been used with great success, reactors have been utilized having a measured inductance for each half winding of approximately 500-1,000 microhenries. In such reactors, the magnitude of the leakage inductance has been found to be typically about 0.2 microhenry.

While there has been shown and described a specific embodiment of the present invention, it will, of course, be understood that various modifications and alternative constructions may be made without departing from the true spirit and scope of the invention. Therefore, it is intended by the appended claims to cover all such modifications and alternative constructions as fall within their true spirit and scope.

What is claimed as the invention is:

1. The improvement of spark discharge control means comprising the combination of a plurality of parallel aligned pairs of spark electrodes, said spark electrodes defining a plurality of parallel spark discharge channels, a source of potential of magnitude sufficient to enable a spark discharge to take place in each pair of spark electrodes, a plurality of balancing reactors, each comprising

7
8
ing reactor windings having end terminals and an intermediate tap terminal, circuit means connecting each of said spark electrodes to a different end terminal of said reactor windings, and circuit means connecting the intermediate tap terminals of the balancing reactors to said source of potential for simultaneous energization of said spark electrodes such that any difference in potential across said spark electrode pairs is balanced by said control means to equalize the current flows in said electrode pairs.

2. The improvement of spark discharge control means comprising the combination of two pairs of parallel aligned spark electrodes, said spark electrodes defining two parallel spark discharge channels, a source of potential of magnitude sufficient to enable a spark discharge to take place in said pairs of spark electrodes, a pair of balancing reactors, each comprising reactor windings having end terminals and a center tap terminal, first circuit means connecting each of said spark electrodes to a different end terminal of said reactor windings, and second circuit means connecting the center tap terminals of the balancing reactors to said source of potential for simultaneous energization of said spark electrodes such that any difference in potential across said spark electrode pairs is balanced by said control means to equalize the current flows in said electrode pairs.

3. The improvement of spark discharge control means in accordance with claim 2 wherein each of said reactors comprises a laminated steel core having a pair of windings connected at said center tap terminal, said windings being wound in opposite directions on said core.

4. The improvement of spark discharge control means in accordance with claim 2 wherein said second circuit means comprises a power switch and storage capacitor means connected to said power switch for applying energizing potential to said balancing reactors upon closing of said power switch.

5. The improvement of spark discharge control means comprising the combination of three pairs of parallel aligned spark electrodes, said spark electrodes defining three parallel spark discharge channels, a source of potential of magnitude sufficient to enable a spark discharge to take place in each pair of spark electrodes, a plurality of balancing reactors, each comprising reactor windings having end terminals and an intermediate tap terminal, circuit means connecting each of said spark electrodes to a different end terminal of said reactor windings, and circuit means connecting the intermediate tap terminals of the balancing reactors to said source of potential for simultaneous energization of said spark electrodes such that any difference in potential across said spark electrode pairs is balanced by said control means to equalize the current flows in said electrode pairs.

6. The improvement of spark discharge control means comprising the combination of three pairs of parallel aligned spark electrodes, said spark electrodes defining three parallel spark discharge channels, a source of potential of magnitude sufficient to enable a spark discharge to take place in each pair of spark electrodes, four balancing reactors, each comprising reactor windings having end terminals and an intermediate tap terminal, circuit means connecting the four spark electrodes in two of said electrode pairs to a different end terminal of the reactor windings of two balancing reactors, circuit means connecting each of the remaining two balancing reactors between the center tap terminals of the first two balancing reactors and a spark electrode of the remaining electrode pair, circuit means connecting the intermediate tap terminals of said remaining two balancing reactors to said source of potential for simultaneous energization of said spark electrodes such that any difference in potential across said spark electrode pairs is balanced by said control means to equalize the current flows in said electrode pairs.

7. The improvement of spark discharge control means

in accordance with claim 6 wherein said intermediate tap terminals of said remaining two balancing reactors is connected to the reactor windings of the latter such that one-third of each reactor winding lies between one end terminal and the intermediate tap terminal and two-thirds of each reactor winding lies between the other end terminal and the intermediate tap terminal.

8. The improvement of spark discharge control means in accordance with claim 7 wherein each of said remaining two balancing reactors comprises a laminated steel core having three layers of windings thereon, the innermost and outermost winding layers having equal numbers of turns, and the middle winding layer having half as many turns as the innermost and outermost layers, and being wound in the opposite direction with respect to said innermost and outermost layers.

9. The improvement of spark discharge control means in accordance with claim 8 wherein the windings of said middle layer are double the diameter of the windings of said innermost and outermost layers.

10. The improvement of spark discharge control means comprising the combination of four pairs of parallel aligned spark electrodes, said spark electrodes defining four parallel spark discharge channels, a source of potential of magnitude sufficient to enable a spark discharge to take place in each pair of spark electrodes, at least six balancing reactors, each comprising reactor windings having end terminals and a center tap terminal, circuit means connecting each of said spark electrodes to a different end terminal of said reactor windings, and circuit means connecting the center tap terminals of the balancing reactors to said source of potential for simultaneous energization of said spark electrodes such that any difference in potential across said spark electrode pairs is balanced by said control means to equalize the current flows in said electrode pairs.

11. The improvement of spark discharge control means comprising the combination of four pairs of parallel aligned spark electrodes, said spark electrodes defining four parallel spark discharge channels, a source of poten- 40

tial of magnitude sufficient to enable a spark discharge to take place in each pair of spark electrodes, six balancing reactors, each comprising reactor windings having end terminals and a center tap terminal, circuit means connecting the spark electrodes of two of said pairs to a different end terminal of two of said reactor windings, circuit means connecting the spark electrodes of the remaining two pairs to a different end terminal of two other reactor windings, circuit means connecting the remaining two reactor windings between the center tap terminals of the first four reactor windings, and circuit means connecting the center tap terminals of said remaining two reactor windings to said source of potential for simultaneous energization of said spark electrodes such that any difference in potential across said spark electrode pairs is balanced by said control means to equalize the current flows in said electrode pairs.

12. The improvement of spark discharge control means comprising the combination of four pairs of parallel aligned spark electrodes, said spark electrodes defining four parallel spark discharge channels, a source of potential of magnitude sufficient to enable the spark discharge to take place in each pair of spark electrodes, three pairs of balancing reactors, each comprising reactor windings having end terminals and a center tap terminal, circuit means connecting two pairs of said spark electrodes to a different end terminal of one pair of balancing reactors, circuit means connecting the remaining two pairs of spark electrodes to a different end terminal of a second pair of balancing reactors, circuit means connecting the third pair of balancing reactors between the center tap terminals of the first and second pair of balancing reactors, and circuit means connecting the center tap terminals of the third pair of balancing reactors to said source of potential for simultaneous energization of said spark electrodes such that any difference in potential across said spark electrode pairs is balanced by said control means to equalize the current flows in said electrode pairs.
